(57) **CLAIM**

The ornamental design for a flashlight, substantially as shown and described.

DESCRIPTION

FIG. 1 is a perspective view of a flashlight incorporating the design;

FIG. 2 is a top view thereof;

FIG. 3 is a bottom view thereof;

FIG. 4 is a left-side elevation view thereof;

FIG. 5 is a right-side elevation view thereof;

FIG. 6 is a front view thereof; and,

FIG. 7 is a back view thereof.

The broken lines showing features on the back of the flashlight are for environmental purposes only and form no part of the claimed design.

1 Claim, 4 Drawing Sheets
